UNITED STATES PATENT OFFICE.

HERBERT E. PRATT, OF NEW YORK, N. Y., ASSIGNOR TO GOULD STORAGE BATTERY COMPANY, A CORPORATION OF NEW YORK.

BATTERY-PLATE SEPARATOR.

1,056,299.

Specification of Letters Patent. Patented Mar. 18, 1913.

Application filed March 25, 1912. Serial No. 685,973.

To all whom it may concern:

Be it known that I, HERBERT E. PRATT, a citizen of the United States, and a resident of New York, county of New York, and State of New York, have invented certain new and useful Improvements in Battery-Plate Separators, of which the following is a specification.

My invention relates to separating means for the plates of storage batteries and the like.

One object of my invention is to provide a new separating means for such plates which will keep the corners and edges of the plate from coming together, keep them from crushing the wood or pervious separating sheets used in such batteries, and which will prevent lead growths from one plate to another about the edges of the separator, thus avoiding short circuits.

Further objects, features and advantages will more clearly appear from the detailed description given below taken in connection with the accompanying drawing which forms a part of this specification.

In the drawing, Figure 1 is a perspective illustrating two battery plates with one form of my improved separating means therebetween, certain parts being broken away to more clearly show the construction; Fig. 2 is a section through a battery cell illustrating a vertical side view of the plates and separating means; Fig. 3 is a horizontal section taken through the parts shown in Fig. 1; Fig. 4 is a similar section but showing a modified arrangement; and Fig. 5 is another similar section but showing a still further modified arrangement.

Referring to Figs. 1, 2 and 3, 1 represents one of the lead plates of a storage battery, which plate may be positive or negative, and 2 indicates the next plate of opposite polarity. 3 is a thin sheet of hard rubber which is finely perforated with holes 4 over its surface except that the side edges 5 are imperforate for a substantial width, as clearly shown in Figs. 1 and 3. The sheet 3 lies adjacent and parallel to the plate 1, and next to the rubber sheet 3 is a sheet of wood separating material 6, such as wood veneer or grooved wood of any suitable or well known kind. Between the sheet 6 and the plate 2 I place another hard rubber sheet 7 which is perforated with holes 8, except that the edges 9 thereof are left im-

perforate for a substantial width. The plate 7 is made thicker at the edges so that it passes about the end of the narrower sheet 6 to form spacing means 10 which space the two sheets 6 and 7 apart, the space therebetween being shown at 11. As shown in Fig. 3 the portions 10 are recessed to receive the edges of the sheet 6, and are vulcanized to the edges 5 of sheet 3. It will be understood that the rubber sheets 3 and 7 are of material impervious to the electrolyte 12' of the cell, while the wood veneer sheet 6 is made of material which is pervious to the electrolyte of the cell.

When wood veneer alone is used, it necessarily comes into contact with the plates, and this is found to injure or shorten the lives of the plates. But by placing the rubber sheets 3 and 7 between the wood separator 6 and the plates 1 and 2, the wood veneer is kept out of contact with both plates, which preserves the plates very materially. The perforations in the rubber sheets allow of a ready passage for the electrolyte therethrough to act on the plates 80 while the space 11 allows the wood veneer to become evenly permeated with the electrolyte over substantially its entire area. It will be noted that rubber sheets 3 and 7 have their outer faces lying close to and 85 against the inner faces of the plates 1 and 2, and thus these rubber sheets aid in holding the paste or active material in or onto the plates 1 and 2. The wood sheet performs its well known functions while the 90 rubber sheets keep it out of contact with the plates 1 and 2. The corners of the plates 1 and 2 are apt to curl or tend to curl and cut through the wood veneer, forming a short circuit or injuring the same. This is 95 prevented by the interposition of the rubber sheets. Also the firm and rigid hard rubber separating means extends from one plate to the other at the side of the plates so that the tendency of the plates to curl can not cause the hard rubber plates to crush the wood sheet. This is facilitated by making the wood sheet of less width than the plates. Moreover, since the rubber sheets prevent the wood from touching the active plates, 105 the life of the wood separator is greatly prolonged. Also since the wood sheet extends beyond the perforations there is no direct path through the separating means through which short circuits may occur, 110

that is by not perforating the side edges of the sheets 3 and 7, the possibility of lead growths around the edge of the wood veneer 6 is avoided, thus preventing short circuits due to this cause.

The modification shown in Fig. 4 is substantially the same as the form of separating means shown in Figs. 1, 2 and 3, except that a space 12 is formed on the opposite side of the sheet 6 from the space 11 in order that the electrolyte may have more ready access to substantially the entire surface on this side of the wood sheet. This is accomplished by increasing the thickness of the side edges 5 at 13, to provide suitable spacing means to space the sheet 3 away from the wood.

The modification shown in Fig. 5 is substantially the same as that shown in Fig. 4, except that the wood sheet 6 is of the same width as the rubber sheets which are separated thereby and the sheets 3 and 7 are also spaced away from the plates 1 and 2 as at 15 and 16. This is accomplished by increasing the thickness of the side edges 5 and 9 at 17 and 18 to form suitable spacing means. While in this form the electrolyte is given greater space to act on the plates, nevertheless the rubber sheets do not hold the active material in such a beneficial manner, as described in connection with Figs. 3 and 4. Instead of forming the spacing means by increasing the thickness of the side edges 5

and 9, it is obvious that separate spacing strips may be placed adjacent said side edges and the parts secured together in any suitable manner, or both rubber sheets may be made integral with one another.

Although I have described my improvements in great detail and with respect to certain particular embodiments thereof, nevertheless, I do not desire to be limited to such details except as clearly specified in the appended claim, since many changes and modifications may well be made without departing from the spirit and scope of my invention in its broadest aspects.

Having fully and clearly described my invention, what I claim as new and desire to secure by Letters Patent, is:

Separating means for storage battery plates, embracing a separating sheet of material pervious to the electrolyte, and a sheet on each side of said pervious sheet, said last mentioned sheets being perforated and substantially impervious to the electrolyte, and secured together at their side edges about the pervious sheet.

In testimony whereof, I have signed my name to this specification, in the presence of two subscribing witnesses.

HERBERT E. PRATT.
